UNITED STATES PATENT OFFICE.

EDMUND JORDAN, OF BROOKLYN, ASSIGNOR, BY MESNE ASSIGNMENTS, TO
THE PNEUMATIC PRESS COMPANY, OF NEW YORK, N. Y.

PRESS.

SPECIFICATION forming part of Letters Patent No. 512,251, dated January 2, 1894.

Application filed March 9, 1891. Serial No. 384,355. (No model.)

To all whom it may concern:

Be it known that I, EDMUND JORDAN, of the city of Brooklyn, county of Kings, and State of New York, have invented a new and useful 5 Improvement in Presses, of which the following is a specification, reference being had to the accompanying drawings.

My improvement relates more particularly to presses employed for shaping plastic materials, such as soap, but is applicable to the shaping of other materials.

I will describe a press embodying my improvement, and then point out the novel features in claims.

15 In the accompanying drawings, Figure 1 is a plan or top view of a press embodying my improvement. Fig. 2, is a side view of the same. Fig. 3, is an irregular longitudinal section, taken, as indicated, by the line xz , Fig. 20 1, certain parts of the machine being entirely omitted. Fig. 4, is a longitudinal section, taken at the plane of the dotted line xz , Fig. 1, certain parts of the machine being entirely omitted. Fig. 5, is an irregular longitudinal 25 section, taken, as indicated, by the line xy , Fig. 1, certain parts of the machine being entirely omitted. Fig. 6, is a transverse vertical section of certain parts of the machine looking in the direction indicated by the arrow 30 1, marked adjacent to Fig. 1. Fig. 7, is a vertical section of certain parts, taken lengthwise of the machine. Fig. 8, is a vertical section of certain parts, taken lengthwise of the machine; and Fig. 9, is a vertical 35 section of certain parts, taken lengthwise of the machine. Figs. 7, 8 and 9, are made on an enlarged scale.

Similar letters and numerals of reference 40 designate corresponding parts in all the figures.

The frame-work of the machine may be of any suitable construction. As here shown, it consists, essentially, of two side pieces united by stretchers and surmounted by a bed A. 45 The shaping of the material is performed by means of a body section or mold plate B, and two plungers, end sections or formers C' C². In the present instance there are two of the body sections or mold plates, and two pairs 50 of plungers, end sections or formers; the press being organized for shaping two cakes

or quantities of material at the same time. Obviously, the number of body sections or mold plates, and plungers, end sections or formers is immaterial, so far as the principle 55 of my improvement is concerned. As here shown, the body sections or mold plates are formed in one integral structure. They are secured to the bed A by screws or otherwise. Each, in the present instance, has combined 60 with it a feed box C, which is open at the top and at the outer side.

The material to be shaped is introduced into the feed box, and from there carried into the adjacent body section or mold plate by means 65 of a plunger, end section or former C². The material may be introduced through the opening in the top of the feed box, or through the opening in the outer side thereof. Preferably there will be combined with each feed 70 box an automatic feeding mechanism for introducing the material through the side opening of the feed box. I have shown such a feeding mechanism, and it will be best understood by reference to Fig. 6. It comprises a 75 carrier D, reciprocating transversely to the length of the machine in guides d' d², which are coincident with the side opening of each feed box. The guide d' is adjustable toward and from the opposite guide d², owing to the fact 80 that it is secured in place by screws passing through slots formed lengthwise of the machine in lugs extending from said guide d'. This adjustability is to suit different sized cakes or quantities of material. The outer 85 end of each carrier D is pivotally connected to links d³, which are also pivotally connected to the upper end of an oscillating arm d⁴. Each arm d⁴ is mounted upon the stud d⁵, and is provided with an arm d⁶ extending at an 90 angle to it and receiving in its end portion a vertical pin d⁷. The upper end of the pin d⁷ extends through an arm d⁸, which rests upon a washer d⁹ arranged above a spring d¹⁰, which is coiled around the pin d⁷, and at the lower 95 end is sustained by the arm d⁸. Each arm d⁸ is rigidly fastened to a rock shaft d¹¹, extending transversely to the length of the machine and journaled in bearings supported in the frame of the machine. The rock shaft d¹¹ has 100 affixed to it an upwardly extending arm d¹² held against a cam d¹³ by means of a spring

d^{14} extending from the bed A down to the arm d^6 and drawing this arm upward so as to move and hold the arm d^{12} against the cam. When the cam oscillates the arm d^{12} against 5 the resistance of the springs d^{14} the arm d^8 , will press downwardly upon the spring d^{10} , and the latter, by exerting a downward pressure upon the arm d^6 , will oscillate the arm d^4 toward the center of the machine, thereby 10 moving the carriers along the guide-ways formed between the guides d' d^2 for the purpose of propelling the cakes or quantities of material into the feed box C. When the cam d^{13} moves in such a direction as to allow the 15 spring d^{14} to produce a reverse movement of the arm d^4 the carriers D will be moved outwardly so as to permit other cakes or quantities of material to be introduced into the guide-ways in front of the carriers.

20 For the sake of clearness, I have marked the cakes of material with the letter F, wherever they appear.

The plungers, end sections or formers C' are fastened to a cross-head C³ reciprocating 25 along ways c lengthwise of the machine. During the reciprocating movement which they have they enter the body sections or mold plates, and afterward recede from the same. They are not, as here shown, rigidly 30 connected with the cross-head C³, but have their shanks fitted into sockets formed in the cross-head in the direction of the length of the machine, so that the extremities of the shanks will protrude beyond the cross-head 35 and impinge against a spring C⁴. This spring may be fastened to the cross-head by a screw c'. By thus combining the shanks of these plungers, end sections or formers with the cross-head they will be capable of yielding 40 slightly when coacting with the other plungers, end sections or formers C² to press the material. Keys c², extending into slots in the cross-head and also into slots formed in the shanks of the plungers, end sections or formers C', to prevent the latter from turning are 45 provided. The cross-head C³ is at its ends fastened to rods C⁵, which are also fastened to a cross-piece C⁶.

Frames C⁷, severally consisting of upright 50 pieces 2, 3, rods 4, and shanks 5, 6, extending from said upright pieces 2, 3, and working in bearings 7, on the bed plate A, are connected to the cross-piece C⁶. As here shown, the connection is made by rods 8, extending from 55 the shanks 6 through the cross-piece C⁶ and fastened to the latter by means of nuts arranged on opposite sides of it and engaging with screw threads formed on said rods 8.

The frames C⁷ have rollers 9 journaled in 60 their upright pieces 3 to coact with cams C⁸ affixed to the shaft E. These cams acting upon the frames C⁷ move the cross-piece C⁶, rods C⁵, and cross-head C³ in such direction as to cause the plungers, end sections or formers C' to enter the body sections or mold plates B. The reverse movement of these 65 plungers, end sections or formers is produced

by means of springs C¹⁰ fastened to the bed A, or an appurtenance thereof, and also to the cross-piece C⁶. The connection with the cross-piece C⁶ will preferably be made adjustable, as, for instance, by means of screw bolts c³ passing through said cross-piece and having nuts applied to them on opposite sides of the cross-piece. The movement produced by 70 these springs C¹⁰ will be limited by means of lugs c⁴ extending upwardly from the bed A, and coacting with projections c⁵ upon the rods 8, for this purpose. These projections c⁵ will 75 preferably be constructed of or comprised of soft material, such as disks of leather, in order that the motion of the parts produced by the springs C¹⁰ will not be arrested too suddenly.

The plungers, end sections or formers C² are 80 attached to a frame C¹¹, which is fitted to slide-ways c⁶ c⁷ fastened to the bed A. Preferably the shanks of these plungers, end sections or formers will be longitudinally slotted and fastened by screws c⁸ to the frame 85 C¹¹ so as to be capable of adjustment relatively to the latter. The adjustment may be effected by screws c⁹ extending through tapped holes in portions of the frame C¹¹ in rear of the shanks of said plungers, end sections or formers and impinging against the 90 ends of said shanks.

The frame C¹¹ is provided with a roller c¹⁰ which bears against a cam C¹² affixed to the shaft E. By means of this cam the frame 100 will be moved in a direction to move the plungers, end sections or formers C² away from the body sections or mold plates B. The frame C¹¹ is also provided with a roller c¹¹ which coacts with a cam C¹³ affixed to said 105 shaft E. This cam moves the frame C¹¹ in such direction as to cause the plungers, end sections or formers C² to enter the body sections or mold plates B.

As represented, the material to be pressed 110 will be introduced into the feed boxes after being already formed into cakes, and will be pressed for the purpose of giving it its final shape. The faces of the plungers, end sections or formers may be ornamented to produce any ornamental surface on opposite 115 sides of the cakes, and to imprint or delineate letters thereon, if this is desirable. After the pressing within the body sections or mold plates the cake will be carried by the plungers, end sections or formers C² entirely through the body sections or mold plates. The cakes will then drop through a hole a' 120 formed in the bed A, onto any part designed to receive them. In the present instance a 125 carrier G is arranged beneath this hole in the bed, and, as here shown, consists of an endless band passing around pulleys f' f², said band running in the direction indicated by the arrow marked upon it in Fig. 1. The 130 cakes after being carried away by the band may be removed from it in any suitable way, as, for instance, by hand. The roller f' is journaled in a bracket A', which may be fas-

tened to the floor. The roller f^2 is affixed to a shaft F' , which is journaled in a bracket a^2 depending from the bed A , and a bracket a^3 affixed to one of the side pieces of the machine frame. The shaft F' has affixed to it a bevel gear wheel f^3 which meshes with the gear wheel h affixed to an upright shaft which is journaled in the bracket a^3 and has affixed to its upper end a bevel gear wheel h' . The bevel gear wheel h' engages with a bevel gear wheel e affixed to the shaft E . By this train of wheels motion is transmitted from the shaft E to the shaft F' . The shaft E is driven from the main shaft I of the machine through a pinion i mounted on this shaft and engaging with a gear wheel e' affixed to the shaft E . Gas or air is employed in this machine for the purpose of facilitating the detachment of the cakes of pressed material from the plun-
gers, end sections or formers $C' C^2$. The plun-
gers, end sections or formers $C' C^2$ are con-
structed in essentially the same manner; hence the construction of both sets may be under-
stood from Fig. 9, which illustrates one of the
plun-
gers, end sections or formers C' . It will be seen that a gas chamber c^{12} is formed in the rear portion of this plunger, end section or former, and that a passage c^{13} extends horizontally from such gas chamber to the
operative face of the plunger, end section or former. This passage is enlarged at the operative end of the plunger, end section or former to accommodate a valve or ejector c^{14} . From the latter extends rearwardly through the passage c^{13} a rod c^{15} which is provided within the gas chamber c^{12} with a valve c^{16} . The space between the valve or ejector c^{14} and the valve c^{16} is greater than the distance between the gas chamber c^{12} and the enlarged portion of the passage c^{13} , which constitutes a seat for the valve or ejector c^{14} ; hence when the valve or ejector c^{14} is seated so as to close the passage c^{13} the valve c^{16} will be moved away from the passage c^{13} , and conversely when the valve c^{16} closes against the end of the passage c^{13} the valve or ejector c^{14} will be moved away from its seat. By means of this combination of parts the passage of gas from the gas chamber to the faces of the cake of pressed material which are in contact with the operative faces of the plun-
gers, end sections or formers $C' C^2$ may be controlled. The gas used will preferably be compressed air, and will be conducted to the plun-
gers, end sections or formers $C' C^2$ by pipes c^{17} of flexible material, such as india rubber, leading from a valve box C^{14} . These pipes c^{17} communicate with the upper parts of the plun-
gers, end sections or formers C' but com-
municate with the shanks of the plun-
gers, end sections or formers C^2 and communicate with the gas chambers of the latter by horizontal passages in their shanks. The valve box C^{14} communicates through a pipe C^{15} with a container or reservoir C^{16} of gas.

The valve box C^{14} has two rotary valves c^{18} fitted to it. Each has a single port which

may be brought into line with a port c^{19} com-
municating with a pipe c^{17} and communicat-
ing with a passage c^{20} , which receives gas 70
from the pipe C^{15} . When these valves are os-
cillated, they either open or close the port c^{19} .

I will now describe how the valves c^{18} are operated. At the ends they extend through the valve box and each has extended through 75 one of its ends a cross pin c^{21} . A spring c^{22} is fastened at one end to each pin c^{21} and at the other end to the valve box. It oscillates each valve far enough to bring its pin c^{21} into contact with a stop pin c^{23} . When the valves 80 are in such positions that their pins c^{21} rest against the stop pins c^{23} , the valves close the ports c^{19} , and no gas flows to the gas cham-
bers c^{12} of the plungers, end sections or formers $C' C^2$. Tappets $J' J^2$ serve to oscillate the 85 valves against the resistance of the springs c^{22} for the purpose of opening the ports c^{19} . They are fastened to the sliding plate C^{11} and are so arranged that the valve controlling the admission of gas to the gas chambers of the 90 plungers, end sections or formers C' , will be opened slightly before the valve which controls the admission of gas to the other plungers, end sections or formers C^2 . The gas is admitted to the gas chambers of the plungers, 95 end sections or formers C' at the instant that the latter begin to recede from the position in which they operate upon the material within the body sections or mold plates, but gas is admitted to the gas chambers of the plungers, end sections or formers C^2 when they 100 eject the material from the body sections or mold plates. After gas has been admitted to the gas chambers of the plungers, end sec-
tions or formers, it will flow through the pas-
sages c^{13} thereof, and as soon as the relaxa-
tion of pressure permits of the moving of the 105 valves or ejector c^{14} outwardly, the latter will be so moved by the pressure of gas, and there-
upon gas will escape from the gas chambers 110 and detach the pressed cakes. The flow of
gas will be only momentary, because the
valves c^{12} will close the passages c^{13} and cut
off communication between the gas chamber
and the passages c^{13} . 115

The supply of compressed air in the reser-
voir or container C^{16} is maintained by means
of a pump, K , operated by an eccentric k af-
fixed to the main shaft I .

In pressing some materials, it is desirable 120 to lubricate the body sections and I will now describe means for that purpose. L designates a reservoir of liquid, which may be vinegar. It has a tubular stem which com-
municates with a valve box l , and the latter 125 communicates with the gas reservoir or con-
tainer C^{16} . The valve box has fitted to it an
oscillating valve l' having two ports. Motion
is imparted to this valve through an arm l^2
connected by a rod l^3 with an arm l^4 , moved 130
in one direction by a cam l^5 mounted on the
shaft E and in the other direction by a spring
 l^6 . This cam is mainly circular, but has at
one point a peripheral depression and at an-

other point a peripheral projection. Normally the valve will be held in such position as to close the tubular stem of the reservoir L, as well as the passage which leads to the gas reservoir or container C¹⁶. From the valve box l, pipes l⁷ l⁸ extend to the top of the body sections or mold plates near the extremities thereof. These pipes extend horizontally from the valve box and the hollow stem 10 of the reservoir L and the passage which leads to the gas reservoir or container C¹⁶ are vertical. The ports of the valve are bent so that when the valve is in one position, it may close and prevent the passage of either the lubricating contents of the reservoir or the gas in the container C¹⁶ from passing it. It may be adjusted to another position to establish communication between the gas container and one of the pipes l⁷ or l⁸. In addition to the 15 ports, the valve l' has pockets l⁹ l¹⁰. Before either set of the plungers, end sections or formers is to be lubricated, one of these pockets will come opposite the tubular stem of the reservoir L and receive a quantity of liquid 20 therefrom. Afterward it will be carried round to a position opposite one of the pipes l⁷ or l⁸, and, as at this time, communication will be established by one of the ports between this pipe l⁷ or l⁸ and the gas container C¹⁶, a puff of air 25 will pass from the latter into such pipe carrying with it a spray of the liquid in a pocket. The depression in the cam l⁵ will cause the oscillation of the valve l' into a position to effect the discharge of lubricating liquid to 30 one end of the body sections or mold plates and the projection of the cam will adjust the valve to effect the discharge of liquid to the other end of the body sections or mold plates. It is intended that the sprays of liquid shall 35 be applied to the faces of the plungers, end sections or formers. The cam operating the plungers, end sections or formers C² is so shaped that just before the discharge of the lubricating liquid which is intended to be 40 supplied to the faces of these devices, the latter will be moved backward for a short distance to expose them to the lubricating liquid. The plungers, end sections or formers C' 45 have the lubricating liquid deposited upon them before they have entered the body sec-

tions or mold plates to their full extent. After receiving the liquid, they are moved still farther inward to cover the opening through which the liquid entered.

What I claim as my invention, and desire 55 to secure by Letters Patent, is—

1. In a press the combination with opposite plungers, end sections or formers and a body section or mold plate, of a reservoir for lubricating liquid, a gas container, and a valve 60 controlling the communication of said gas container with the molding devices whereby the lubricating liquid may be caused to pass to said molding devices, substantially as specified. 65

2. The combination with a gas container and a movable end section or former, of a valve intermediate of the gas container and end section or former, a gas conduit leading from the gas container to the end section or former and within which the valve is located, and mechanism substantially such as described for automatically operating said valve, substantially as specified.

3. The combination with a gas container, 75 of end sections or formers receiving gas from said gas container, each having a gas chamber communicating with the operative end of the end section or former, valves in said end sections or formers for controlling the 80 passage of gas and a valve between the gas container and end sections or formers operating to admit gas to one of said end sections or formers in advance of the other, substantially as specified. 85

4. The combination with opposite plungers, end sections or formers and a body section or mold plate, of a reservoir for lubricating liquid, a gas container, and a valve controlling the passage of lubricant to the formers, said 90 lubricant being ejected by gas from the gas container, substantially as specified.

In testimony whereof I have signed my name to this specification in the presence of two subscribing witnesses.

EDMUND JORDAN.
